Attorney

UNITED STATES PATENT OFFICE.

THOMAS H. MURRAY, OF NIAGARA FALLS, NEW YORK.

COLLAR BUTTON.

Application filed January 30, 1924. Serial No. 689,572.

To all whom it may concern:

Be it known that I, THOMAS H. MURRAY, a citizen of the United States, residing at Niagara Falls, in the county of Niagara and

5 State of New York, have invented new and useful Improvements in Collar Buttons, of which the following is a specification.

This invention relates to an improved button for use on collars, cuffs and the like, the 10 general object of the invention being to make the button so that it can be easily passed through the buttonholes and also to provide it with locking means for locking it in the hole.

15 This invention also consists in certain other features of construction and in the combination and arrangement of the several parts, to be hereinafter fully described, illustrated in the accompanying drawing and 20 specifically pointed out in the appended claims.

In describing my invention in detail, reference will be had to the accompanying drawing wherein like characters denote like 25 or corresponding parts throughout the several views, and in which:—

Figure 1 is a perspective view of the button in closed position.

Figure 2 is a similar view of the button in 30 open position.

Figure 3 is an edge elevation thereof.

Figure 4 is a view showing the application 35 of the button to a collar.

As shown in these views, the button consists of a base 1, a stem 2 and a head 3. I prefer to form the button from a blank of material and to then bend the stem at its junction with the base and head so that a substantially Z-shaped member is formed. 40 The head is connected with the stem adjacent one end and the other end of the head is pointed to facilitate its passing through a buttonhole. A locking member 4 is pivotally attached to the large end of the head and this member is of substantially the same shape as the head. It is provided with a lip 45 so that when the member is in a position under the head to permit the head to be passed through a buttonhole, by pressing on this lip the member can be swung from 50 under the head so as to form an extension of the head and thus hold the button in the

hole. When in open position, one edge of the locking member will bear against the stem which acts as a stop for preventing 55 further movement of the member.

From the foregoing, it will be seen that when the locking member is in position under the head, the part of the button which is to be passed through the buttonholes is 60 offset from the stem with its free end pointed so that it can be easily passed through the holes. After the button is in place, the locking member is moved outwardly by pressure upon its lip until it extends in the 65 same plane as the head and thus forms a head of the same length as the base which firmly holds the button in place.

It is thought from the foregoing description that the advantages and novel features 70 of my invention will be readily apparent.

I desire it to be understood that I may make changes in the construction and in the combination and arrangement of the several parts, provided that such changes 75 fall within the scope of the appended claims.

What I claim is:—

1. A button of the class described comprising a base, a stem and a head and a locking member pivotally connected to the under side of the head at one end thereof so that it can be moved to a position under the head to permit the head to be passed through a buttonhole and then moved to form an extension of the head to hold the button in the 85 hole.

2. A button of the class described comprising a base, a stem and a head formed of one piece of material with the stem extending at an angle to the head and base and a member pivoted to the under side of the head at the end which is connected with the stem and a lip on said member.

3. A button of the character described comprising a base, a stem and a head, a locking member of like shape as the head pivotally secured thereto and normally lying in parallel engagement therewith, and a lip formed on said locking member to move the same out of engagement with the head for 100 the purpose specified.

In testimony whereof I affix my signature.

THOMAS H. MURRAY.
